UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed March 12, 1925. Serial No. 14,917.

My invention relates to mining apparatus.

An object of my invention is to provide an improved mining apparatus. Another object of my invention is to provide an improved mining apparatus especially adapted to use with the "panel" system of mining. Still another object of my invention is to provide an improved mining apparatus having a novel form of elongated cutter bar and including improved means for driving the cutter chain and for feeding the machine relatively to the work. A further object of my invention is to provide an improved mining apparatus comprising a novel organization wherein a plurality of power units are provided for driving the cutter chain. A still further object of my invention is to provide an improved mining apparatus having improved feeding means therefor. A still further object of my invention is to provide an improved mining apparatus having an elongated cutter bar of novel form and including improved feeding means therefor acting at each end of the cutter bar whereby the latter may be fed relatively to the work. These and other objects and advantages of my invention will, however, hereinafter more fully appear.

In the accompanying drawings I have shown for purposes of illustration two forms which my invention may assume in practice.

In these drawings,—

Fig. 1 is a plan view of my improved mining apparatus, the apparatus being shown undercutting a panel.

Fig. 2 is a side elevational view of the apparatus shown in Fig. 1.

Fig. 3 is a modified form of the mining apparatus shown in Fig. 1.

In the illustrative embodiment of my invention shown in Figs. 1 and 2 I have provided a plurality of unitary mining machines, generally designated 1 and 2, respectively, which herein are of a usual room and pillar type and which are slidable on their bottoms on the mine bottom in the usual manner and each of the machines comprises a motor section 3 housing a usual reversible motor, not shown, and a feed and cutter chain driving section 4, the latter section housing a plural

speed feeding mechanism including a usual feed operating member 5 herein in the form of a chain sprocket. The feed operating member 5 is rotatable on a vertical axis and is adapted to be driven in opposite directions 55 at a fast and at a slow speed in a well known manner. Furthermore, cooperating with each of the feed operating members 5 is a flexible feeding element 6, herein in the form of a feed chain. As illustrated, the feed chain 6 60 is guided by a plurality of guide sprockets 7 rotatable on vertical axes and disposed adjacent the feed operating member 5 and guide sprockets 8 disposed adjacent the opposite sides of the forward end of the machine 65 frame. As the specific structure of the above mining machines does not per se enter into my invention, it is believed that further description of the same is unnecessary.

In my improved construction and organization it will herein be observed that each of the feed chains 6 is adapted to cooperate with the feed operating member 5 and adapted to be extended from this feed operating member around certain of the guide sprockets 7, along the side of the machine frame, around the guide sprocket 8 at the advancing side of the machine frame, and forwardly from the machine along the side of the panel of the coal. The feed chain is then adapted 70 to pass around a guide sprocket 9 secured, as by a roof jack 10, in advance of the machine, the feed chain then passing rearwardly and is adapted to be secured, as at 11, to the advancing side of the machine frame, 75 thus forming a double strand feeding connection which substantially reduces the usual feeding speed of the machine. As illustrated, disposed between and supported by the unitary mining machines 1 and 2 is an elongated 80 horizontally disposed rigid cutter bar 12 projecting longitudinally from the machine frames and about which an endless cutter bit carrying cutter chain 13 is adapted to be circulated, the cutter chain being driven at 85 each end thereof by means of usual cutter chain sprockets, not shown, driven from the mining machine driving motors in a well known manner. It is obvious that a rotary type cutter bar may be used if desired. 100

In the form of my invention shown in Fig. 3 I have provided a plurality of unitary mining machines, generally designated 15 and 16, which are herein of the usual longwall type having their machine frames angularly disposed with respect to the cutter bar 12 and locked with respect thereto by means of usual detachable locking pins 17. As shown, these mining machines are slidable on the mine bottom and each comprises a motor section 18, a feed section 19, and a cutter chain driving section 20, the sections 19 and 20 being disposed at each end of the motor section 18 and rigidly secured thereto in any suitable manner. The feed sections 19 of each of the machines house feeding mechanism including a feed operating member 21, similar to the feed operating member 5, heretofore described, and this feed operating member 21 cooperates with a feed chain 22 which is adapted to be extended longitudinally of the machine and around a guide sheave 23 secured at a point in advance of the machine. The chain 22 is adapted to be extended rearwardly from this guide sheave 23 and secured to the forward end of the machine frame, as at 24. The cutter chain driving sections 20 house suitable mechanism including usual cutter chain driving sprockets, not shown, which are each adapted to simultaneously drive the cutter chain 13.

In the operation of both forms of the machines heretofore described, it will herein be noted that the machines are disposed in substantially parallel entries and the cutter bar is extended transversely of the panel of coal to be undercut. The feed chains are then extended from the feed operating members around the guide sprockets on the machine and the stationary guide sprockets in advance of the machine and the free ends thereof are secured to the machine frames. The driving motors are then started and the cutter chain circulated about the cutter bar at a relatively high speed. The operators then connect the feed operating members in operative driving relation with the driving motors and the machine is fed relative to the feed chains at the desired cutting speed and the cutter bar is fed under the coal, the double strand feeding connections substantially reducing the normal feeding speed of the machine, this speed reduction being necessitated because of the unusually long cutter bar, which in some cases is one hundred feet in length. If it is desired to feed the machine in the opposite direction the driving motors are reversed, the cutter bits turned in their respective links, and the feed chains extended in a reverse manner relative to the feed operating members and connected to the opposite sides of the machine frames.

As a result of my invention an improved mining apparatus is provided especially adapted to use with the "panel" system of

mining wherein improved and simplified feeding and cutting means are provided. It will further be noted that an improved mining apparatus especially adapted to use with the "panel" system of mining is provided wherein standard room and pillar or longwall mining machines are preferably utilized although the invention is not limited thereto, and combined in a novel manner with a single connecting rigid cutter bar, the unitary mining machines preferably used forming separate driving and feeding means for each end of the cutter bar, but single driving means might obviously be used. Other advantages of my invention will be clearly apparent to those skilled in the art.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A mining apparatus comprising spaced transportable supports each having a driving motor and feeding means driven thereby, and cutting mechanism driven by one of said motors including a movable cutting device and an elongated rigid guide for said cutting device along which the latter is movable, said guide extending between said supports and wholly supported thereon at its ends.

2. A mining apparatus comprising spaced transportable supports each having a driving motor and feeding means driven thereby, and cutting mechanism including an elongated rigid cutter bar extending between and supported at its ends by said supports, said cutter bar having an endless cutter chain orbitally movable about its outer edges, and driving connections between said motors and said cutter chain.

3. A mining apparatus comprising spaced transportable supports slidable on their bottoms on the mine bottom and each having a driving motor and feeding means driven thereby, and cutting mechanism driven by said motors including an orbitally movable cutting device and an elongated rigid guide for said cutting device along which the latter is movable, said guide extending between and wholly supported at its ends by said supports.

4. A mining apparatus comprising spaced transportable supports each having a driving motor and feeding means driven thereby, and cutting mechanism including an elongated horizontal rigid cutter bar extending between and supported at its ends by said supports, said cutter bar having an endless cutter chain orbitally movable about its outer

- edges, and driving connections between said motors and said cutter chain.
5. A mining apparatus comprising spaced transportable supports each having a driving motor and feeding means driven thereby, and cutting mechanism including a rigid cutter bar extending between and supported at its ends by said supports, said cutter bar carrying and guiding cutting devices, and means driven by said motors for actuating said cutting devices relative to said cutter bar to cut a kerf to admit said bar.
10. A mining apparatus comprising a pair of spaced mining machines slideable on their bottoms on the mine bottom and each having a driving motor and feeding means driven thereby, and cutting mechanism including an elongated cutter bar extending between and supported at its ends by said machines and having an endless cutter chain orbitally movable about its outer edges, and driving means carried by each of said machines and driven by said motors for actuating said cutter chain.
15. A mining apparatus comprising spaced transportable supports each having a driving motor and feeding means driven thereby, said supports being slideable on their bottoms over the mine bottom during feeding, and cutting mechanism including an elongated rigid cutter bar extending between and supported at its ends by said supports and carrying and guiding movable cutting devices, and means driven by said motors for actuating said cutting devices relative to said cutter bar to cut a kerf to admit said bar.
20. A mining apparatus comprising spaced transportable supports each having a driving motor and feeding means driven thereby, and cutting mechanism including a rigid cutter bar connecting said supports and carrying and guiding movable cutting mechanism, and means driven by said motors for actuating said cutting mechanism relative to said cutter bar to cut a kerf to admit said bar, said feeding means being adapted to cause travel of said supports and bar in a direction substantially transverse to the longitudinal axis of said bar.
25. A mining apparatus comprising spaced transportable supports each having a driving motor and feeding means driven thereby, and cutting mechanism including a rigid cutter bar and a cutter chain carried by said bar, spaced transportable supports one at each end of said bar, means on one of said supports for actuating said cutter chain, and feeding means carried by each of said supports including a driving motor and feeding devices actuated thereby for moving said supports by power from said motors in a direction substantially transverse to the longitudinal axis of said bar.
30. A mining apparatus comprising spaced transportable supports slideable on their bottoms on the mine bottom and each having a driving motor and feeding means driven thereby, an elongated movable cutting device and an elongated rigid guide extending from one support to the other for said cutting device along which the latter is movable, said guide being wholly supported at its ends on said supports, and means driven by said motor for actuating said cutting device relative to said guide to cut a kerf to admit said guide, said feeding means being adapted to move said supports in a direction substantially transverse to the longitudinal axis of said cutting device and guide.
35. A mining apparatus comprising spaced transportable supports slideable on their bottoms on the mine bottom and each having a driving motor and feeding means driven thereby, each of said feeding means including a double strand flexible connection, and cutting mechanism including a movable cutting device and an elongated rigid guide for said cutting device along which the latter is movable, said guide extending between said supports and wholly supported at its ends thereon, and means driven by said motors for actuating said cutting device relative to said guide to cut a kerf to admit said guide.
40. A mining apparatus comprising a plurality of spaced mining machines each having a driving motor, and cutting mechanism including a single rigid elongated horizontal cutter bar extending between said machines and supported at its ends thereon, said cutter bar having an orbitally movable cutter chain guided thereon about its outer edges, and driving connections between said motors and said cutter chain.
45. A mining apparatus comprising spaced transportable supports, cutting mechanism extending between said supports and having one end thereof supported by one of said supports and the other end thereof supported by the other of said supports, said cutting mechanism including a rigid guide supported wholly by said supports and carrying an endless cutter bit carrying cutter chain movable in a horizontal plane in a fixed orbit which extends from one of said supports to the other and surrounds said guide, driving means for actuating said cutter chain, and means for feeding said supports.
50. A mining apparatus comprising spaced transportable supports each having individual thereto a driving motor and feeding means driven thereby, and cutting mechanism including a rigid bar supported wholly by said supports and carrying an endless cutter bit carrying cutter chain movable in a horizontal plane in a fixed orbit about the periphery of said bar, said cutter bar being connected at its ends to said supports, and driving means for actuating said cutter chain.
55. A mining apparatus comprising spaced transportable supports, a rigid elongated cutter chain supporting and guiding member extending between and supported at its ends by said supports, an endless cutter bit carrying

cutter chain engaging said guide member directly and movable between said supports in a fixed orbit on said guide member, and driving means carried by said supports and operatively connected to said cutter chain for actuating the latter.

16. A mining apparatus comprising spaced transportable supports, a rigid elongated cutter chain guide member extending between 10 and supported at its ends by said supports, an endless cutter bit carrying cutter chain movable between said supports in direct engagement with and in a fixed orbit on said guide member, and driving means carried by 15 one of said supports and operatively connected to said cutter chain for actuating the latter.

17. A mining apparatus comprising spaced transportable supports, cutting mechanism 20 carried by said supports including a movable cutting device and an elongated rigid horizontal plane guide for said cutting device along which the latter is movable between said supports to cut a horizontal kerf, said 25 guide extending from one support to another and wholly supported on said supports at its opposite ends and means for feeding said supports at a cutting speed in a direction at right angles to the direction of motion of said 30 cutting device along said guide between said supports.

18. A mining apparatus comprising spaced transportable supports slidable on their bottoms directly on the mine bottom during the 35 cutting operation, feeding means for said supports, and cutting mechanism carried by said supports including a movable cutting device and an elongated rigid guide for said cutting device along which the latter is movable, said guide extending from one support 40 to the other and wholly supported on said supports at its ends.

In testimony whereof I affix my signature.
MORRIS P. HOLMES.
